FIG.1

FIG.2

FIG.3

FIG. 4

FIG. 5

FIG. 6

FIG. 7

FIG. 1 is a front elevational view of a cervical collar embodying my new design;

FIG. 2 is a left side elevational view of the cervical collar of FIG. 1;

FIG. 3 is a rear elevational view of the cervical collar of FIGS. 1 and 2;

FIG. 4 is a side perspective view of a modified embodiment of the cervical collar;

FIG. 5 is a front elevational view of the cervical collar of FIG. 4 in the open condition with the lower portion thereof detached;

FIG. 6 is a side elevational view of the cervical collar of FIGS. 4 and 5 with the lower portion telescoped upwardly; and

FIG. 7 is a view similar to FIG. 6 with the lower portion of the cervical collar telescoped downwardly.

The broken lines in the various views represent stitching.

This is a continuation-in-part of design application Ser. No. D. 4,953, filed Dec. 7, 1966, and now abandoned.

I claim:

The ornamental design for a cervical collar, as shown and described.
